METHOD OF MAKING JEWELRY CHAINS

Frederick W. Bopp, Providence, R. I.

Application February 4, 1935, Serial No. 4,979

1 Claim. (Cl. 59—35)

This invention relates to a chain mainly designed for jewelry purposes, the general object of the invention being to provide a flexible core and a plurality of tubular members placed on 5 the core to provide a tube chain.

This invention is a continuation in part of an application filed by me on May 17, 1934, Serial No. 726,151.

This invention also consists in certain other 10 features of construction and in the combination and arrangement of the several parts, to be hereinafter fully described, illustrated in the accompanying drawing and specifically pointed out in the appended claim.

15 In describing the invention in detail, reference will be had to the accompanying drawing wherein like characters denote like or corresponding parts throughout the several views, and in which:

Fig. 1 is an elevation of a length of chain constructed in accordance with this invention.

20 Fig. 2 is a fragmentary view, with parts in section.

Fig. 3 is a view, with the tube in section, showing how the tube is cut into short lengths by a 25 spinning operation.

Fig. 4 is a fragmentary longitudinal sectional view, the section being taken at right angles to that of Fig. 2.

In this drawing, the numeral 1 indicates a chain 30 which is composed of the links 2 having rounded ends, and in carrying out the invention, a plurality of short tubes 3 is placed on the chain so that the chain forms a core or filler and each end of each tube has an inwardly extending part 4 which is engaged by a rounded link of the chain 35 so that each tube has but limited sliding movement on the chain.

The invention is carried out by placing an elongated tube over the chain and then cutting the tube into short lengths and deforming the ends to provide the inwardly extending parts 4 which limit sliding movement of the tubes on the chain. 5

This operation is performed by a spinning process as shown in Fig. 3, which shows one part of a tube being separated from another part by the spinning action of a rotating member 5 carried by a shaft 6. This spinning process displaces 10 the middle of the tube inwardly until a point is reached where the metal parts, so that one part of the tube is separated from another part, the displaced metal extending inwardly to form the inwardly extending portions 4. Of course, 15 as many of the members 5 are used as are necessary to divide the tube into the desired number of parts.

The tube is severed at points which intersect 20 certain of the links midway between the ends of said links as shown in Figs. 2 and 4 and during the spinning operation, the side members of said links are indented as shown at 7 by the spinning actions. The beveled spinning wheel leaves the 25 ends of the tube sections slightly beveled as shown.

I claim:

The herein described method of forming a tube chain consisting in placing a long tube over a chain, then cutting the tube into short lengths 30 by spinning operations which press the metal at the ends of the short lengths inwardly to form interior projections at the ends of the short lengths, said projections engaging portions of the chain. 35

FREDERICK W. BOPP.
